CLAIM

The ornamental design for a device cover, as shown and described.

DESCRIPTION

FIG. 1 is a perspective view of a device cover, taken from above;

FIG. 2 is a front view of the device cover as shown in FIG. 1;

FIG. 3 is a back view of the device cover as shown in FIG. 1;

FIG. 4 is a left-side view of the device cover as shown in FIG. 1;

FIG. 5 is a right-side view of the device cover as shown in FIG. 1;

FIG. 6 is a top view of the device cover as shown in FIG. 1; and,

FIG. 7 is a bottom view of the device cover as shown in FIG. 1.

The broken lines represent features of the device cover which form no part of the claimed design.

1 Claim, 5 Drawing Sheets
